(57) **CLAIM**

I claim the ornamental design for a corner protector, as shown and described.

DESCRIPTION

FIG. 1 is a left side perspective view of the corner protector; FIG. 2 is a right side perspective view of the corner protector of FIG. 1;

FIG. 3 is a top view of the corner protector of FIG. 1; FIG. 4 is a bottom view of the corner protector of FIG. 1; FIG. 5 is a left side elevation view of the corner protector of FIG. 1;

FIG. 6 is a front elevation view of the corner protector of FIG. 1; and,

FIG. 7 is a right side elevation view of the corner protector of FIG. 1.

The broken lines in the drawings illustrate portions of a corner protector that form no part of the claimed design.
